UNITED STATES PATENT OFFICE

NATHANIEL CATTERALL, OF BROMLEY CROSS, NEAR BOLTON, ENGLAND
DEVICE FOR CHECKING OR ARRESTING SHUTTLES WITHIN THE SHUTTLE BOXES
OF LOOMS

Application filed May 1, 1929, Serial No. 359,482, and in Great Britain May 4, 1928.

My invention relates to shuttle checking apparatus or to shuttle arresting devices within the shuttle boxes of looms of the type or class wherein the swell lever in the 5 shuttle box is made use of for contacting with the shuttle, as it enters said shuttle box, to bring about the gradual arresting of its motion in a more desired manner than heretofore, thereby securing benefits which are 10 fully known to those who have a knowledge of the use of looms.

My present invention consists in the employment of cam actuated lever devices so constructed and arranged that they may be 15 readily adjusted and when mounted in position will control the actions of the swell lever so that same is brought into use at the exact time desired relative to the other actions of the loom in order to carry out the 20 gradual retarding and arresting of the motions of the shuttle under the best possible conditions for securing said arresting of the shuttle without causing excessive wear, deterioration and breakages.

In order that my said invention may be 25 readily understood I have hereunto appended sheets of drawings illustrative thereof to which by figures and letters reference is made in the following description:—

Fig. 1 is a sectional end elevation of sufficient of the end frame of a loom, the slayboard, the laysword and the crank shaft of said loom with other parts in connection therewith to illustrate the application of 35 my improved devices. The said parts are shown in the respective positions that they occupy when my improved devices are not exercising any pressure on the swell lever of the loom.

Fig. 2 is a sectional plan of the parts shown by Fig. 1.

Fig. 3 is a similar plan to Fig. 2 but illustrates a modification hereinafter described.

Fig. 4 is a similar view to Fig. 1 but 45 illustrates my improved devices when in position for applying the maximum pressure upon the swell lever of the loom.

A indicates the slayboard of the loom, B the laysword, C the crank shaft and D the 50 end frame of the loom.

In all the drawings these parts are shown on one end of the loom only, but it is to be understood that the same parts arranged in their respective positions are employed at the other end of the same loom so that 55 by describing the devices at one end of the loom it will readily be understood how their actions may be brought into use at both ends of the looms.

The crank shaft C is coupled in the usual 60 manner to the slayboard A by the arms or connecting rods c.

In carrying my invention into effect in connection with the type of loom illustrated by Figs 1, 2 and 4 wherein the crank shaft 65 C is so situated, between the two end frames D of the loom, that a space exists between the sweep of the crank C and said end frame D to enable the adjustably fixing in position upon said crank shaft C, of a cam 70 2 which is preferably of the shape shown by Figs. 1 and 4.

The cam 2 is arranged to actuate a lever 3 which is pivoted at 40 to the end frame D at the rear of the loom, while said lever 75 3 is so shaped that it will extend over said cam 2 for its extremity 3a to reach towards the front of the loom. By this arrangement of devices as the crank shaft C revolves so will the cam 2, which is fixed thereon, revolve, and this revolving of the cam 2 will cause the lever 3 to rise and will allow it by gravity to descend at the exact time that the picking or throwing of the shuttle necessitates to meet the requirements of the 80 85 checking actions of the swell lever 14 hereinafter described.

By the employment of the cam 2 which is adjustably fixed by pinching screws or otherwise upon the crank shaft C I am enabled to regulate or adjust said cam 2 in any desired position upon the crank shaft C so that it will meet the requirements stated exactly and with precision.

The front or extending end 3a of the lever 95 3 is so arranged that a runner 4a mounted upon a stud carried at the end of a lever 4, will travel over the upper surface of said extending end 3a. Thus said lever will transmit motion vertically to the runner 4a 100

and lever arm 4 in order that this latter may oscillate loosely upon the sword pin 5 to enable the extension or adjustable finger 7, secured to said lever 4, to come into contact with the extending end of a spring member 8 which is fixed upon the vertically extending finger 9 known as the back stop rod finger of the loom.

This back stop rod finger 9 which is of 10 spring steel extends downwardly to be adjustably fixed upon an extension 9a from the main stop rod 9b used in the loom in well known manner while the back stop rod finger 9 is arranged to contact with the outer 15 end 14a of the swell lever 14. This lever 14 is pivoted at 14b upon a bracket carried by the slayboard A in well known manner.

As will be observed the lever 4 may have the finger or attachment 7 which is secured 20 to it by screws 7a, so adjusted that said projecting member 7 will at all times be in contact with the spring 8 that is fixed to the back finger 9 above described.

The devices hereinbefore described are 25 brought into operation at the desired time by the adjustment of the cam 2 upon the crank shaft C so that when the shuttle is entering the shuttle box the lever 3 will commence to rise and will gradually force 30 the lever 4, the extension 7 carried by said lever 4, and the spring 8 to press more and more upon the back finger 9 to cause this latter to press upon the swell lever 14 to carry out the checking or retarding actions 35 gradually as the shuttle is entering the shuttle box in known manner. By the several parts being made adjustable, the said actions of the devices may be regulated to take place at the desired time and under conditions which will prevent wear and deterioration 40 as is hereinbefore stated.

The stop rod or shaft 9b is of the well known type of stop rod used in looms and extends from my devices which are mounted 45 on one end of the loom to similar devices mounted on the opposite end of the loom so that the checking of the shuttle is carried out at both ends of the loom by my devices being used in said two positions.

50 The cam 2 is shown by Figs. 1, 2 and 4 to be mounted upon the crank shaft C within the end frames D in looms where the position of the crank is such as will permit said cam 2 to be fixed upon said shaft in said position, whereas in looms in which the crank shaft C is too close to the end frame D to permit said cam so to be mounted then said cam 2 may be mounted upon the outer ends 55 of the crank shaft C as is shown by Fig. 3 in which case the supporting bracket for the stud 40 (upon which the lever 3 is mounted) will extend outwardly from the end frame D to the lever 3 mounted upon it. In this case the lever arm 4 is mounted upon a short shaft 5a which is supported by brackets 5b

and 5c fixed to the slayboard A while the vertical flat-spring 7b is fixed upon the short shaft 5a in the position shown by Fig. 3 so that it may contact with the upper end of the back finger 9 which is fixed upon the ordinary stop rod 9b of the loom where the swell lever 14 is mounted upon the slayboard A in the usual manner.

Provided the well known toothed wheel 10 and balance wheel 11 (shown by Fig. 3) 75 which are carried by the crank shaft C are sufficiently far apart to permit the lever 3 to extend between them then the cam 2 may be mounted upon the crank shaft C between said two wheels.

The arrangement of my devices as is hereinbefore described enables the employment of my cam actuated devices in connection with looms in which the crank shaft revolves in one direction to beat up the weft as well as in connection with other looms wherein the crank shaft revolves in the opposite direction to beat up the weft since the actions of my cam are the same in both cases and its adjustment in position relative to the sweep 90 of the crank can be effected as desired.

Such being the nature of my said invention what I claim is:—

1. In devices for checking or arresting shuttles within the shuttle boxes of looms, 95 the combination with the loom crank shaft, slay board and longitudinal stop rod, of a cam mounted on the crank shaft and capable of adjustment, a pivoted lever cooperating with the cam, a second lever having a projection engaging the lever cooperating with the cam, means for pivotally mounting the second lever on the slay board, a flat spring, means for securing said flat spring to the stop rod, and a second projection on the 100 second lever adapted to contact with the flat spring.

2. In devices for checking or arresting shuttles within the shuttle boxes of looms, 110 the combination with the loom crank shaft, slay board, swell lever and longitudinal stop rod, of a cam mounted on the crank shaft and capable of adjustment, a pivoted lever cooperating with the cam, a second lever pivotally mounted on the slay board 115 and adapted to engage the lever cooperating with the cam, a vertically projecting spring, an extension from the stop rod in which the vertically projecting spring is adjustably fixed, a projection engaging the spring and operated by the second lever, a second spring 120 extending horizontally from the vertically projecting spring to intervene between it and the projection, and means for securing the second spring to actuate in conjunction with 125 the swell lever.

NATHANIEL CATTERALL.
